UNITED STATES PATENT OFFICE.

WILLIAM RAGAN BINKLEY, OF NEW BEDFORD, MASSACHUSETTS, ASSIGNOR OF ONE-HALF TO EDWARD E. CLEMENT, OF WASHINGTON, DISTRICT OF COLUMBIA.

AUTOMATIC TELEPHONE-EXCHANGE SYSTEM.

1,093,525.

Specification of Letters Patent.

Patented Apr. 14, 1914.

Application filed July 22, 1905. Serial No. 276,852.

To all whom it may concern:

Be it known that I, WILLIAM R. BINKLEY, a citizen of the United States, residing at New Bedford, in the county of Bristol and State of Massachusetts, have invented certain new and useful Improvements in Automatic Telephone-Exchange Systems, of which the following is a specification, reference being had therein to the accompanying drawing.

My invention relates to automatic telephone exchange systems, and has for its object the production of a system of this kind wherein certain improvements are possible in the mechanical movements of the switches employed, and wherein party-line selective service may be given, and in general the operation may be improved and the apparatus simplified.

In its broadest aspect my system comprises a percentage trunking scheme; that is, it employs a trunk selector or "A" switch for each line, whose sole function is to seize upon and temporarily connect its line when calling, with an idle trunk and first selector switch, which in turn will select and seize upon other idle switches in desired groups, there being a smaller number of these selector switches than there are lines, the successive groups bearing a definite percentage relation to the number of lines. Thus, of first selector switches I may employ five per cent. or ten per cent., or in very busy exchanges even fifteen per cent. (the total number of subscribers' lines being taken as one hundred per cent.). Of second selector and connector switches I may employ the same percentages. Selection of any desired line is made, first by causing the "A" switch of the calling line to seize upon an idle first selector switch; then through this first selector seizing upon an idle second selector in the desired thousands group; then through this second selector seizing upon an idle connector in the desired hundreds group; then through the connector effecting contact with terminals in the desired tens group and finally the desired terminals in that group; then testing these terminals to ascertain if the line wanted is busy; then if the subscriber wanted is on a party-line, selecting the proper current to ring his station; and finally to send such current to line. This current is sent over what I call the private normal wires, and upon examina-

tion of my circuits hereinafter described, it will be observed that I have found means to enable a subscriber to ring back upon his own line and call another subscriber on that line, without getting any of the ringing current himself, and without his telephone interfering with the ringing current. From this general statement it may be seen that the basis for my system is a percentage trunking arrangement, the success of which has been fully demonstrated in commercial practice, and to which I have added A switches (or line switches) which effect the initial connection between calling lines and the trunking net work, selective party-line ringing means, a scheme for mechanical development and simplification of the switches, and certain circuit connections and arrangements, together with relay and magnet windings required thereby, all of which will be fully described hereinafter. I also attain, however, the difficult ends of giving party-line service and employing a common battery as the source of current supply for all purposes.

I shall present herein a design for a switch which I desire to have taken as typical only. Such switches are always modified after having been used awhile, and I am aware that many details may and probably will in course of time undergo change. Nevertheless, the distinguishing features of the type I consider characteristic, and that they will be permanent. In this switch I employ four principal magnets, and in connection with each two relays. The contact arms or wipers have a rotary motion only, there being no double motion employed. Three sets of wipers and three banks of contacts are employed. Set No. 1 effect the selection; set No. 2 effect the test and also shift a common actuating magnet mechanically from set No. 1 to set No. 3, the latter then advancing until an idle trunk of the selected group is reached. The test sets of the A, B and C switches have three possible positions, one being "normal," the second an extreme position for test, and the third an intermediate position occupied during conversation. In the D or connector switch, there is a fourth position, which is necessary in order to select the proper ringing current for party-line signaling. The test wipers in a typical switch are mounted on a common hub, the No. 1 wipers are mounted on another

common hub, and the No. 3 wipers on still another common hub. Each set of wipers moves together as a unit, and it is by interconnection from the wipers of one set to the bank contacts of another set in the same switch that I am enabled to avoid the use of separate movements and mechanical parts. To put the matter in a word, instead of having the same wiper step up and then around, with two motions, as in the Strowger system, I have two sets of wipers which act in succession and coöperate to produce the same result. Moreover, I only employ one stepping magnet for both movements, instead of two as heretofore.

An important feature of my invention, especially considered with the common battery feature, is the employment of a two-wire circuit. Of course, it is necessary in any system of this kind to provide for distinguishing between working impulses and what I may designate as control impulses. The working impulses are transmitted over the circuit in groups of ten or less, while the control impulses serve to change the connections during the intermissions between the groups of working impulses, so that each group may reach the particular apparatus for which it is intended. In the Strowger systems and others the control impulses are sent over one side of the line and the working impulses over the other, the necessary shifting being effected by means of what is called a side switch. I supply current to both sides of my line from the common battery for the transmitter at the substation, which then propagates voice currents into the metallic circuit through the medium of an induction coil; and in order to differentiate between the signal impulses I divide them into those which require both sides of the line to be grounded (or working impulses), and those which require only one side of line to be grounded (or control impulses), and finally those which require the other side of line to be grounded (or release impulses). To attain my ends I employ differentially wound relays of novel and peculiar type, which I shall claim hereinafter. One of these relays has a pair of differential windings included *seriatim* in a branch metallic circuit from line to battery. Another of these relays has three equal windings, one of which is individual to one side of the branch metallic circuit from line to battery through a second or common coil. The third coil is individual to the other side of the branch metallic circuit from line to battery also through the second or common coil, joining the first at a common point of entrance to the second coil. The connections of these windings are such that the individual and the common coil from one side are reversed to each other as to magnetic effect, while from the other side the individual and

common are in the same direction as to magnetic effect. The individual coils of this relay form a second differential relay in series with the first or plain differential relay, which when taken together form a bridge to the metallic circuit of very high magnetic reactance to high frequency currents, and a balanced circuit to direct current, flowing over both sides to supply the primary of the transmitter.

The first relay I employ for testing, and the second one for working the switches. Working impulses are sent over both sides of the lines simultaneously and hence do not affect the plain differential test relay, but do affect the working relay, since the individual coils only oppose each other, while the common coil receives the united current from both lines and is effective.

For testing purposes, I ground that side of the line which contains the balanced windings of the working relay, whereby the test relay becomes energized, while the working relay remains idle. For the purpose of restoring the apparatus to zero or normal position throughout, I ground the other side of the line in which the individual coil and the common coil of the working relay act together magnetically, whereupon both relays become energized and by their joint action close the release circuits. Each switch has these two relays, the working magnet, the shifting magnet, the selecting magnet, the test magnet, and the release magnet, all of which will be fully described hereinafter.

The method of selective ringing is simple but exceedingly effective, and I consider it to be broadly new. It consists in providing on the connector switch an extra pair of wipers which move with the selecting wipers, and a set of bank contacts connected to the various generators, employed. The line contacts are made of various lengths, so as to cover one or more corresponding generator contacts in point of angular dimensions. Thus, a line may come in and have a broad contact over which the wiper will have to make four steps before it passes on to the next contact. The underlying wiper passes over four different terminals during these four steps, and obviously I may put four parties on the line, giving them successive numbers, and ring them separately, since successive steps will supply different generator currents to the line. There may be one, two, three or four party contacts in the same bank, and the current supplied when those lines are selected will be determined by the underlying generator bank contacts. Moreover a great saving in the wiring in the connector banks is effected, as well as the saving of a large percentage of the connector switches required by most of the automatic systems giving party-line service. For example, for a four-party line

only one set of contacts is required in each bank or in each connector switch of the hundreds group containing the line number. Since one connector supplies the four kinds 5 of ringing current, obviously there is both a great saving of connector switches in my system over other systems requiring quadruple groups of connectors, each adapted to supply but one kind of ringing current to 10 the same line. Furthermore there is a great flexibility in my party-line connector. In a connector to serve one hundred subscribers, I may assign one horizontal row of 15 ten sets of bank contacts for four-party lines, or forty subscribers in all. I may set apart the next two horizontal rows each containing ten sets of bank contacts, for two-party lines, or a total of forty subscribers; and lastly I may have two other rows containing 20 ten sets each of bank contacts, for single party lines, or a total of twenty subscribers. This gives a grand total of one hundred subscribers on fifty sets of bank contacts, all handled by one connector or a 25 percentage group of similar connectors.

I put my ringers in ground taps, in the drawings herewith, but they may be in metallic circuit bridges; and of course during a through connection I have a metallic talking circuit right through from subscriber to subscriber, with a bridge across it however at every switch, or four bridges in all. In each bridge, however, there is a high impedance, for it is observed that the differential windings of my relays which are in the bridges, do not neutralize the magnetic reactance for high frequency currents, although they do destroy the magnetic effects for battery currents. Moreover, four bridges 40 are permitted by standard practice in manual systems.

My invention is illustrated in the accompanying drawings, wherein—

Figure 1 shows four subscribers' stations 45 connected to the same line. These stations receive party-line service and are shown diagrammatically, the sender or transmitter device in each case being represented for convenience by push-buttons instead of the ordinary transmitting device; Fig. 2 represents what I shall call the "A" switch, there being one of these for each subscriber's line; Fig. 3 shows the first selector or "B" switch; Fig. 4 shows the second selector or C switch; Fig. 5 shows the connector or D switch; Fig. 6 shows the means for picking out a 50 certain generator current for selective party-line work; Fig. 7 is a side elevation of the B switch; Fig. 8 is a side view of the 55 switch, showing the magnet O and the parts actuated thereby looking from the left in Fig. 11; Fig. 9 is a side view of the same magnet with its attached parts projected on the end of the frame; Fig. 10 is a longitudinal section of the part s^{22} shown in Fig.

11; Fig. 11 is an elevation showing the several magnets and the parts actuated thereby.

Referring first to Fig. 1, wherein four party-line stations, K, K, K², K³, are shown, the apparatus at all being identical, 70 the various parts will be designated throughout by the same letters or numerals. Referring particularly to station K, the telephone set proper consists of the transmitter T, receiver R, induction coil I, retardation 75 coil N, ringer Q, condensers L², L³, and hook H. One terminal of the transmitter is grounded, the other terminal being connected, when the hook H is up, to both sides of the line through the two windings of the retardation coil N and the primary of the induction coil I. Push-button P of the transmitting device when depressed grounds No. 6 side of the line to operate the trunking magnets of the various switches; the 80 push-button P' grounds both sides of the line simultaneously to operate the switching relays for the various switches; the push-button P² grounds No. 5 side of the line and acts as the release button for the various 85 switches; the push-button P³ when depressed disconnects the ground through coil N from both sides of the line by opening the transmitter circuit which actuates the ringing relay in the D or connector switch. Station 90 K is shown as a calling station, the receiver being removed from the hook.

Before entering into a detailed description and statement of operation of the several different switches and their circuits, the following distinction between them should be carefully noted: The B and C switches are identical and are group as well as "idle-trunk" selectors. On the other hand, the function of the A switch is that of an idle 105 trunk selector only, since its sole function is to connect its line when calling with an idle first selector. Consequently it is without the set of bank contacts designated as "series 1" in the B, C and D switches. Referring to Figs. 7, 8 and 9, it has already 110 been stated that the mechanical features shown are intended to represent a type of mechanism adaptable to the purposes of each of the switches in the system, and not a fixed and unchangeable specific design. The A switch would not require the No. 1 banks at the right of Fig. 7, nor the operating ratchet, pawl, or arm therefor; neither 115 would it require the slide bar s^{22} nor its connecting mechanism; neither would it require a heavy operating magnet as shown at O, a single magnet V being probably sufficient. Thus in design the A switch can be made 120 small and of very simple construction, since "series 3" which represents the banks of the five or ten pairs of trunks leading to the first selector switches, are all that are required for selective purposes. The magnet 125 X in this switch may well combine the dou. 130

ble function of testing and trunking. Again, the connector switch D is the same as the B or C switches, but stripped of its trunk selective function and made to operate series 3 by impulses sent from the subscriber's station through an additional function of series 2, instead of by interrupted current supplied from C, C' or C². It also contains the ringing current selective bank 10 shown as series 4.

Referring now to Fig. 2, the A switch consists of the following: the relay M, which has two windings; a terminal of one winding, m^{20} , being connected to No. 5 side of the line, and the other terminal thereof being connected to the terminal of relay E; a terminal of the second winding, m^{30} , is connected to No. 6 side of the line, the other terminal thereof being connected to a second terminal of the relay E. The relay E itself has three equal windings so arranged that for current flowing over both sides of the line, 5 and 6, simultaneously, it becomes energized; for current flowing over No. 6 20 side of the line only, through two windings, it remains in a neutral state; while current flowing over No. 5 side of the line organizes it. The windings e^0 and e^{10} are in series, oppositely wound, so that current through them both will produce a zero magnetic effect; but with current through all three coils, as would be the case when simultaneous impulses are sent over both line wires 5 and 6, there will of course be a lack of balance, and 30 hence the core of the relay will be magnetized by a current equivalent in ampere turns to twice that of any one of the three windings, when two of them are connected in series. I consider this relay winding a 40 very important feature of my invention, and shall claim it broadly as well as specifically. I believe I am the first to provide means whereby current through one side will not energize a differential relay, but that 45 through both sides will do so. I use this principle throughout my system, as will presently appear.

The relay M has two equal windings, m^{20} , m^{30} , and unlike the relay E it remains in 50 a neutral state while current is flowing over both sides of the line simultaneously and is operative or becomes energized while current is flowing over either side of the line at different intervals. The trunking magnet V 55 is operated when the relay M is energized, by the closing of the contacts m and m' , and this magnet V in turn causes the wipers of series marked 2 to move from what I shall call the a or normal position to what I shall 60 call the c position, which is a trunking or test position. When the relay M becomes deenergized after a certain interval the wipers of series 2 fall back and rest in the b position where they remain throughout 65 conversation. All the wipers of the various

series 2 and 3 normally rest on the first contacts of their respective banks, the advantage of this being that if the first contact is not engaged by some other party there will be no movement of the switch necessary. 70 Bearing in mind also that all of the B switches of the group to which they belong have their similar contacts of series 1 in multiple, it will then be seen that when series 2 occupies the b position all the similar 75 contacts in the test set of series 1 that are multiplied in the switches of the group will be grounded when brought in contact with wiper z^{90} , 33, z^{18} , 44, z^{12} , b , 37, ground. In a similar manner the multiplied test contacts 80 of series 1 of switch C are grounded through wiper z^{21} , 57, z^{29} , 71, z^{24} , b , 67, 68, ground. Those of switch D will likewise be grounded through wiper z^{42} , 85, z^{42} , 100, z^{36} , C (this being the position for conversation), 88, 95, 85 ground. In order to simplify the description, I have shown the test contacts in series 3 of the switch A, and in series 1 of the switches B, C, and D as being directly connected to ground, this being their condition 90 when the switches are busy as described. Now when the wipers of the series 2 are in the c position and the first contact opposite z^8 in series 3 happens to be busy or grounded the test magnet X becomes energized 95 through the following circuit: ground, z^8 , 26, z^7 , c , 13, X, 21, battery B and ground. The magnet X then becomes energized and causes the wipers z^6 , z^7 and z^8 of series 3 to step around until an idle contact is found. 100 The release magnet, W, is connected on one side to contact m' and on the other to contact c so as to be actuated when the relays M and E are energized at the same time. This only happens at the end of a conversation, 105 when the calling subscriber presses his button P² (Fig. 1), and grounds No. 5 side of the line. The relay E is kept energized during conversation by battery flowing over both sides of the line through the transmitter to ground. Its armature remains attracted and breaks the contacts e^2 — e^3 , and e^4 — e^5 , protecting the calling subscriber from interruption while talking to anyone, whether on his own or some other line. The 115 wipers z^4 and z^5 of series 2 terminate in contacts in the banks of the connector switch of their particular group and are the private normals. In this case I have used five per cent. of connector switches so therefore 120 the lines from each station will terminate in their own individual A selectors and the private normals will be connected in multiple to the contacts of the five connector switches each of its particular group.

Referring now to Fig. 3, the B switch consists of the following: relays M' and E', which operate in the same manner as relays M and E in Fig. 2. The relay E' controls the operating magnet O which in turn 130.

causes the wipers z^9 , z^{90} and z^{900} of series 1 to rotate a number of steps corresponding to the number of impulses sent in over both sides of the line simultaneously affecting the relay E' . The magnet O is operated by the relay E' by the following circuit: battery B, 0, 50, z^{10} , a , 40, e^6 , e^7 , 46 to the opposite side of battery. The relay M' is operated by ground being placed on No. 6 side of the line as in Fig. 2, and in turn operates the magnet V' which causes the wipers of the series 2 to take the c position. The B switch picks out the thousands numeral of the line desired. When the wipers z^9 , z^{90} and z^{900} of series 1 come to rest on the contacts corresponding to the number of impulses of the desired line they are connected with the five trunks of the desired thousands in the following manner: The series 1 is made up of five rows of contacts, each row having three wipers, best shown in Fig. 7. These wipers move in unison. The first contact of the first row is connected to the first trunk leading to the one-thousand group; the first contact of the second row is connected to the second trunk leading to the one-thousand group; the first contact of the third row is connected to the third trunk leading to the one-thousand group, and so on. The second contact of the first row is connected to the first trunk leading to the two-thousand group and the second contact of the second row is connected to the second trunk leading to the two-thousand group and so on up to the ten-thousand group. The wipers of the first row are connected to the first contacts in series 3, and the wipers of the second row are connected to the second contacts in the same series. It will readily be seen that when the wipers in series 1 rotate a certain distance, say three spaces, the wipers will rest on the five trunks leading to the three-thousand group, but without effect as yet, since they all remain on open circuit until the wipers in series 3 rotate and pick out one of the trunks which is not busy and close the circuit of the trunk selected. For illustration; suppose the wipers in series 1 had moved to the three-thousand group and that the first trunk was engaged or busy, then a ground would be placed opposite the test wiper z^{900} and the test magnet X' would have its circuit closed and (through the actuation of the operating magnet O) cause the wipers in series 3 to pass the busy contact and take the next one which is not busy. The circuit of the magnet X' is closed through the following path: battery B, 41, X' , 49, 38, c , z^{12} , 44, z^{18} , 33, z^{900} to ground. In attracting its armature it closes the contacts x and x' which in turn close the circuit of the magnet O by the following path: battery B, 41, x' , and x , 39, c , z^{10} , 50, O , to the opposite side of battery. The magnet O now

causes the wipers of the series 3 to rotate and come opposite contacts leading to an idle trunk. It will be noticed that in the first operation the magnet O causes the rotation of series 1, but now it causes the rotation of series 3 alone. After the trunking period the magnet M' becomes deenergized, which in turn deenergizes the magnet V' allowing the wipers in series 2 to assume the b position. The calling subscriber is now connected to the C switch. This switch picks out the hundred numeral of the desired line and being identical with the B switch in Fig. 3 need not be described.

Referring now to Fig. 5, the connector switch D is shown, which consists of the following: differentially wound relay E^2 , which responds to impulses sent in over both sides of the line simultaneously and which in turn controls the operating magnet O^2 which successively controls series 1, 3 and 4. The relay E^2 unlike the relays in the selector switches is operated twice, that is, it transmits first the tens numeral and after that the units numeral. This is brought about by strapping the terminals a and b together in the series 2, so that after the wipers z^{24} and z^{35} move one space they still have the same connection. The relay M^2 , when actuated over No. 6 side of the line, energizes the relay V^2 by closing the contacts m^8 and m^9 . In the connector switch D the energizing of the magnet V^2 moves the wipers of series 2 but one step, that is they assume the b position. The energizing of the relay V^2 makes series 1 inoperative and series 3 operative by the magnet O^2 . After the operation of the tens numeral the spring wipers with reference to the bank of contacts are disposed as shown in Fig. 6 at d' , d^2 , d^3 , d^4 and d^5 , resting on the tens contact of all the numbers in a certain hundred.

A bank of contacts in the sense here intended, consists of a number of contacts arranged in a plane or planes at right angles to an axis and at a predetermined distance apart and from the axis, so that spring wipers attached to a shaft rotated in the axis will come successively into contact with separate contact units in the plane. In my bank there are five such planes with thirty contacts in each. There are also five sets of three wipers each mounted on the shaft, one set for each plane of contacts. The three wipers of a set are placed at an angular distance apart subtending an arc of ten contacts. Two of the contacts are trunks or lines, and the third the test contact, in each set of three.

In Fig. 7, series 1 shows a section in a plane passed through the axis, the contacts being shown in full lines, and the insulation in section. In Fig. 6 I have shown the five horizontal planes of contacts spread out in one plane together with the wipers of each,

and designated them by the symbols d' , d^2 , d^3 , d^4 , d^5 . Thus is series 1 shown complete. Above these in the length of the sheet or on the right of the figure, I have placed series 3 and 4, consisting of but two planes of contacts and wipers. I have arranged them in this order so as to better show their relation, the one to the other. It will be observed that when the shaft is rotated the five sets of 10 wipers will at every step occupy similar or corresponding contacts. It follows that after the operation of the tens numeral the spring wipers with reference to the bank of contacts are disposed as shown in Fig. 6 at 15 d' , d^2 , d^3 , d^4 , d^5 , resting on the tens contacts of all the numbers constituting this bank of contacts. When the impulses representing the units numeral are transmitted over lines 5 and 6, and magnet O^2 is actuated thereby, 20 the wipers of series 3 and 4 of Fig. 6 will be advanced by as many steps as the units numeral represents.

By the arrangement of series 3 being supplied with broad contacts embracing four 25 positions it is evident that the line connections will not be changed for the first four successive impulses. The line contacts will be contained in the section d' and each pair of contacts will represent a four-party line. 30 Again referring to series 3, Fig. 6, it is seen that the next two positions would be embraced in the contact connected with section d^2 and that each pair of contacts would represent a two-party line. Likewise the next 35 two contacts of series 3 would be embraced in a broad contact similar to the two preceding ones and connected with section d^3 . The last two contacts of series 3 are single and connect with d^4 and d^5 , respectively, representing single lines. The selective ringing 40 current for these several different lines is selected as follows: Series 4 of Fig. 6 shows the method of selecting one of four different kinds of ringing current, which may be 45 pulsating or current of different frequency. The first pair of contacts lead to one generator of a certain frequency, the second pair to a generator of another frequency, and the third and fourth pairs to similar generators 50 of different frequencies. In the connector or D switch series 3 and 4 are in one bank and the wipers for the same move in unison occupying similar positions at the same time. This being the case it will be readily seen 55 that the wipers z^{40} and z^{41} , of series 3, will remain unchanged for the first four impulses of the tens numeral, while four different ringing currents are supplied to the contact of the ringing relay Y indirectly 60 connected with the lines 5 and 6 through 101, 102, 86, and 87. In the same manner for the next two contacts in series 3 two different ringing currents will be supplied and also for the next succeeding two, while the last 65 two contacts will be supplied with one kind

only. It will be seen from this that provision has been made for forty four-party, forty two-party and twenty single party lines for each connector or D switch, which makes a total of one hundred in all. After 70 the tens numeral has been transmitted the impulses for the unit numeral are sent in over both sides of the line simultaneously affecting the relay E^3 the second time, which operates the magnet O^2 , which now in turn 75 operates series 3 corresponding to the unit numeral of the line desired. After the unit numeral has been sent in impulses are sent in over No. 6 side of the line, affecting the relay M^3 , which in turn operates the trunking 80 magnet V^3 , which advances series 2 to the d position. After a certain interval allowing for a test to be made for a busy line, series 2 assumes the c position in the same manner as the selector switches assume the b position. 85 If the line is busy the following conditions will prevail: The contact occupied by the wiper z^{32} will be grounded by some switch occupying some multiple of it rendering it busy, and then the following circuit be completed: ground, z^{32} , 85, z^{42} , 100, z^{36} , d , 89, d , 86, 104, v^{15} , v^{16} , 105, 90, V^3 , 94 to battery B. This circuit will be maintained after the trunking period is terminated, that is after the ground connection from No. 6 side of 95 line at the telephone is broken and will be maintained so long as the line is held busy. While this is held busy we have the following indication of it: G^5 is a generator or busy-back producing a characteristic sound 100 to act as a busy signal to the calling subscriber. This signal is conveyed to the calling subscriber by the following circuit: ground, G^5 , 98, v^{12} , v^{13} , 103, z^{37} , d , 86, y , y^5 , L' , 82, 55, through the switches C, B and A 105 to ground through the calling subscriber's telephone. The ringing relay is operated after series 2 has assumed the c position and the calling subscriber disconnects ground from both sides of the line by pushing the 110 button P^3 , which opens the transmitter circuit. The relay E^3 , as well as the similar relays in the selector switches, becomes de-energized, the armature of the relay E^3 falling back closing the contacts e^{10} and e^{11} , 115 which closes the circuit of relay Y by the following path: battery B, 94, Y , 99, c , z^{39} , 96, m^7 , 97, e^{10} , e^{11} , 95 to the opposite side of battery. The relay Y when energized for 120 ringing opens the contacts y^4 , y^2 , y^3 and y , opening the line of the calling subscriber to prevent generator current being sent back. In the case of calling a party on the same line, generator current is sent back to the calling line over the private normals by the 125 following path: 86, c , z^{37} , 103, v^{12} , v^{14} , 102, z^{41} , 84, z^{31} , private normal 24; and in Fig. 2, z^5 , 9, e^5 , e^4 , 8, line No. 6 through the called subscriber's ringer to ground. The release magnets W , W' , W^2 and W^3 are operated 130

when the called subscriber depresses the release button, which grounds No. 5 side of the line, energizing the pair of differentially wound relays in each switch, thereby closing 5 the circuits of their respective release magnets.

In Fig. 7 I have shown a selector switch B to operate in connection with the foregoing circuits. While this switch fulfills all 10 the necessary conditions, I do not wish to be limited to the exact construction, as I have stated before. A switch can be designed in various ways to embody and render useful the principle of my invention. It will be 15 recognized at once the switch has but one motion, *yiz.*, a rotary motion, consisting, however, of the successive rotation of wiper series 1, 2 and 3, in their order. These series correspond to those similarly numbered in 20 the other figures. The operating magnet O has the double arms s and s' carrying the engaging pawls s¹⁴, s¹⁶, respectively, which when in proper position engage alternately the toothed hubs s⁹ and s¹², causing the rotation 25 of series 1 or 3, as the case may be. When the magnet V is energized it draws down the armature carrying the arm s², which supports the pawl s³. The pawl engages the tooth s²⁵ of the wheel s⁴ and draws 30 it down a certain distance and turns the wheel s⁴. To the spindle of the wheel s⁴ there is fixed a crank arm s⁵, carrying a guide s²⁶. On the under face of this guide are two projections, best shown in Fig. 10. 35 One of these projections, when the wheel s⁴ is in the normal or *a* position, permits the pawl s¹⁴ to engage the hub s⁹ which actuates series 1. The other projection comes in the path of the pawl s¹⁶ when V is energized 40 and s⁴ is rotated into the *c* or test position. In this position, the projection which normally engaged s¹⁴ is now out of engagement, leaving this pawl inoperative with reference to its hub s⁹. In the connector switch the 45 wheel s⁴ has two teeth s³³ and s⁴⁴. The tooth s³³ is situated below the position of the tooth s²⁵, when the wheel is in its normal position, at such a distance that when the pawl s³ of the connector switch is operated it does 50 not engage the tooth s³³ until the latter part of its movement. This results in turning the wheel s⁴ and the wipers carried thereby one space instead of two. The arm s⁵ and the bar s²⁶, however, are arranged to be 55 shifted during this one step. A subsequent actuation of the arm s⁵ engages the tooth s⁴⁴ which is so placed on the wheel s⁴ that the latter is moved two spaces. It will be observed that 1st, series 1 will be operated 60 while the wheel s⁴ is in the normal position, *a*, and 2nd, that series 3 will be in the operative position when the magnet V is energized, *i. e.*, when the wheel s⁴ is in the *c* position. After the magnet V is deener- 65 gized, the pawl s³ engages the tooth s⁹, which

allows the wheel to drop back just one space, or to the *b* position, instead of allowing it to fall back to normal or the *a* position. The wipers of series 1 are operated upon the movement of the shaft s²⁸, to which the toothed hub s⁹ is rigidly fixed. The wipers of series 3 are mounted on the sleeve s¹³ moving freely on the shaft but fixed rigidly to the toothed hub s¹². The operating magnet O performs two functions: It operates 70 series 1, and also operates series 3, depending only upon the guide arm carrying the projections to cause the proper pawl to engage its respective hub. On the end of the frame are shown the differentially wound relays E and M. 75

Figs. 8, 9 and 10 show the operation of the two pawls very clearly. Fig. 10, while merely fragmentary in itself, shows the guide or slide bar s²⁶ together with the cam projections which engage the two pawls and force them alternately into operative relation with their respective gears. The release magnet W' works to release the switch on the break, that is to say, when energized 80 by a pulse of current, it pulls up its armature and a hook pawl carried thereby passes up over the horizontal finger of the detent pawl, pulling down and releasing the latter when the current impulse ceases. This 85 is a necessary condition for positively releasing switches in series in most systems. If any switches were released on the make instead of the break, they might cut off those beyond before their magnets had a chance to work, but by making the release on the break, all the magnets will pull up, having plenty of time to do so, and then when the break comes they will all let go, irrespective 90 of the connections between them. 95

Fig. 9 shows the trunking relay in addition to the operating magnet O. I have not deemed it necessary to show all the contacts on the various relays employed in my switches, since these may be of any well understood construction and are not claimed herein. 100

The switch shown in Figs. 7, 8 and 9 is typical of the various switches employed. It will be observed, however, that there are 110 only two series of contacts in the A switch, the series 1 of the typical switch together with its operating magnet O being omitted, while in the switch D there is a fourth series of contacts 4 lying immediately beneath the 115 series 3 and whose wipers are moved simultaneously with the wipers of series 3. The controlling magnet X' is also omitted from this switch since this is a connector switch and does not require an intermittently actuated magnet for selecting an idle trunk. 120

The operation of my system is as follows: The subscriber first depresses the button P which disconnects the telephone set by breaking the contacts p and p' and grounds 130

No. 6 side of the line by closing the contacts p' and p^2 . In a transmitting device the depressing of this button would not be required as No. 6 side of the line would be grounded in the act of setting up the desired number. Ground coming in on No. 6 side of the line energizes relay M which attracting its armature, closes the contacts m and m' which in turn close the circuit of the trunking relay V through the following path: battery B, 20, m , m' , 18, z , a , 17, V, 21, to the opposite side of battery B. The relay V becoming energized closes the contacts v^2 and v^3 which serve to keep the relay energized after the wipers in series 2 have left the a position and as long as there is a ground on No. 6 side of the line. The contacts v and v' are disconnected, preventing a ground entering series 3 over wire 28. The energizing of the relay V causes series 2 to move to the c position and if the first trunk happened to be busy, as in this case we have shown it to be by placing a ground on the contact leading to wiper z^8 , the magnet X, which is connected to one side of the battery through the constantly actuated commutator C, would become energized and cause series 3 to step around until an idle trunk was found. The first trunk being busy, the circuit of the magnet X is completed by the following path: battery B, 21, X, 23, 13, c , z' , 26, z^8 , to ground. After the trunking period is passed, that is after the prolonged ground has been removed from No. 6 side of the line at the substation the relay M becomes deenergized and releases the magnet V which allows series 2 to fall back to the b or trunked-through position. The calling subscriber is now connected through to the B switch by the following path: lines 5 and 6, z^2 , and z^3 , 27 and 28, z^6 and z^7 , 15 and 16, to an idle B switch. The calling subscriber now depresses the button P' which places ground on No. 6 side of the line by the following path: ground, p' , p^{15} , 152 and 6. Ground is also placed on No. 5 side of the line by the following path: ground, p^1 , p^{15} , p^6 , 151, 5. The contacts p^3 and p^4 are broken as are p^5 and p^6 , disconnecting the talking set. Ground now being placed on both sides of the line simultaneously, the relay E' becomes energized and attracting its armature, closes the contacts e^6 and e^7 which closes the circuit of the operating magnet O by the following path: battery B, O, 50, z^{10} , 40, e^6 , e^7 , 46, to the opposite side of battery. The calling subscriber depresses the button P' a number of times corresponding to the thousands numeral of the desired line, and the relay E' and the magnet O are operated correspondingly. The operation of the magnet O causes the wipers in series 1 to step around the number of spaces corresponding to the thousands numeral of the line desired. After sending in the impulses

for the thousand numeral, the subscriber again depresses the button P grounding No. 6 side of the line, which operates the magnet M' closing the contacts m^2 and m^3 which in turn closes the circuit of the trunking magnet V' by the following path: battery B, 41, V', 42, a , z^{11} , 34, m^2 and m^3 to the opposite side of battery. The energizing of the magnet V' as in the case of the A switch causes series 2 to take the c position. When the magnet V' is energized it closes the contacts v^6 and v^7 maintaining its circuit through these so long as the ground is placed on No. 6 side of the line. If, after series 2 has assumed the c position the first trunk happens to be busy as in this case I have shown it to be by placing a ground on the contact leading to the wiper z^{11} , the magnet X' will become energized over the following path: ground, z^{11} , 33, z^{18} , 44, z^{12} , c , 38, 49, X', 41, to battery. The relay X' thereupon attracts its armature and closes the contacts x and x' completing the circuit of the operating magnet O by the following path: battery B, O, 50, z^{10} , 39, x , x' , 41, to the opposite side of battery. The magnet X' in operating closes the contacts x and x' which in turn closes the circuit of the operating magnet O by the following path: battery B, 41, x' , x , 39, c , z^{10} , 50, O, to the opposite side of battery. The energizing of the magnet O the second time instead of advancing series 1 as before now advances series 3. This advance movement is kept up so long as the circuit of the magnet X' is kept closed by the wiper z^{11} finding a grounded or busy contact. As soon as an idle or free contact is found the circuit of the magnet X' is broken and the contacts x and x' are broken which stops the operation of the operating magnet O and the wipers of series 3 come to rest on an idle trunk in the desired thousand. After the trunking period, that is after ground is removed from No. 6 side of the line at the substation the relay M' becomes deenergized, the wipers of series 2 assume the b position and the calling subscriber is connected through the A and B switches to the C switch. The circuit is as follows: 151, 5, b , z^3 , 27, z^6 , 15, 30, b , z^{14} , 43, z^{10} , 31, z^9 , 35 to the C switch, also 152, 6, b , z^2 , v , v' , 28, z^7 , 16, 29, b , z^{13} , v^5 , v^4 , 45, z^{17} , 32, z^{90} , 36, and to the C switch. The next step in the order of calling will be for the calling subscriber to push the button P' the number of times corresponding to the hundred numeral of the desired line. The depressing of this button operates the relay E² in the same manner that E' in the B switch was operated, in fact the operation of the C switch is identical in every respect with that of the B switch. The relay E² attracting its armature closes the contacts e^8 and e^9 which closes the circuit of the 120

operating magnet O' by the following path: battery B, 68, O' , 66, z^{22} , 63, e^8 , e^9 , to the opposite side of battery. The calling subscriber depresses the button P' a number of 5 times corresponding to the hundred numeral of the desired line and the relay E^2 and the magnet O' are operated correspondingly. The operation of the magnet O' causes the wipers in series 1 to step around a number 10 of spaces corresponding to the hundred numeral of the desired line. After sending in the impulses for the hundred numeral the subscriber again depresses the button P grounding No. 6 side of the line which operates the magnet M^2 closing the contacts m^4 and m^5 which in turn closes the circuit of the trunking magnet V^2 by the following path: battery B, 62, V^2 , 74, a , z^{23} , 64, m^4 , m^5 , 65 to the opposite side of battery. The 15 energizing of the magnet V^2 as in the case of the A and B switch causes the series 2 to take the c position. When the magnet V^2 is energized it closes the contacts v^{10} and v^{11} maintaining its circuit through these so long 20 as ground is placed on No. 6 side of the line even after the wipers of series 2 have left the a position. If, after series 2 has assumed the c position, the first trunk happens to be busy as in this case I have shown it to be by 25 placing a ground on the contact leading to the wiper z^{21} , the magnet X^2 will become energized over the following path: ground, z^{21} , 57, z^{20} , 71, z^{24} , c , 61, X^2 , 62 to the opposite side of battery. The relay X^2 thereupon 30 attracting its armature closes the contacts x^2 and x^3 which in turn closes the circuit of the operating magnet O' by the following path: battery B, 62, x^2 , x^3 , 60, c , z^{22} , 66, O' , 68 to the opposite side of battery. The energizing of 35 the magnet O' this time instead of advancing series 1 as before now advances series 3. This advance movement is kept up so long as the circuit of the magnet X^2 is kept closed by the wiper z^{21} finding a grounded or busy 40 contact. As soon as an idle or free contact is found the circuit of the magnet X^2 is broken as are the contacts x^2 and x^3 which stops the operation of the operating magnet O' and the wipers of series 3 come to rest on an idle 45 trunk in the desired hundred. After the trunking period, that is after ground is removed from No. 6 side of the line at the substation the relay M^2 becomes deenergized and the wipers of series 2 assume the b 50 position and the calling subscriber is now connected through the A, B and C switches to the connector or D switch, by the following circuit: 35, 52, b , z^{26} , 70, z^{27} , 53, z^{19} , 55, into Fig. 5, 82 and M^3 by parallel branches: 55, also 36, 51, b , z^{25} , 72, v^9 , v^8 , 69, z^{28} , 54, z^{20} , 56, into Fig. 5, 81 and M^3 by parallel branches, the divided windings of magnets M^3 and E^3 being bridged across the wires 55 and 56 as shown in Fig. 5 and the wires 81 and 82 60 constituting the talking circuit. The next 65

step in the order of calling will be for the calling subscriber to push the button P' a number of times corresponding to the tens numeral of the desired line. The depressing of this button grounding both sides of the line operates the relay E^3 in the same manner the corresponding relays were operated in the other switches. The relay E^3 attracting its armature closes the contacts e^{12} and e^{13} which in turn completes the circuit of the operating magnet O^2 by the following 70 path: battery B, 95, O^2 , 91, a , z^{34} , 93, e^{12} , e^{13} , to the opposite side of battery. The operation of this magnet O^2 causes the wipers in series 1 to step around a number of spaces 75 corresponding to the tens numeral of the desired line. The relay E^3 when energized also breaks the contacts e^{10} and e^{11} which jointly control the circuit of the ringing relay Y as will be explained later. Following 80 the sending in of the tens numeral is the usual trunking period. The button P being depressed grounds No. 6 side of the line and operates the relay M^3 which attracting its armature closes the contacts m^8 and m^9 completing the circuit of the trunking magnet V^3 by the following path: battery B, 94, V^3 , 90, a , z^{35} , 104, 92, m^8 and m^9 , 95, to the opposite side of battery. The energizing of the magnet V^3 in this case instead of advancing 90 the series 2 two spaces as in the case of the former switches advances it but one space to the b position. The magnet V^3 as in the case of the corresponding magnets in the other switches maintains its circuit through the 95 closing of the contacts v^{15} and v^{16} . It will be noticed that the contacts occupying the positions a and b belonging to the wipers z^{34} and z^{35} are connected together. This is done to allow the magnet O^2 to be operated a second 100 time for sending in the unit numeral of the desired line. The energizing of the relay M^3 breaks the contacts m^6 and m^7 which jointly control the circuit of the ringing relay Y .

After the operation of the tens numeral 110 just described the spring wipers with reference to the bank of contacts are disposed as shown in Fig. 6 except that they would rest on the tens contact of all the numbers in a certain hundred. By the arrangement 115 of series 3 being supplied with broad contacts embracing four positions it is evident that the line connection will not be changed for the first four successive impulses. The method of supplying generator current of 120 any frequency has been fully described.

The next step in operation after the trunking period will be to send in the unit numeral of the desired line. The subscriber depressing the button P' grounds both sides of the line and operates the relay E^3 which attracting its armature closes the contacts e^{12} and e^{13} completing the circuit of the magnet O^2 instead of advancing the series 1 advances 130

series 3 a number of spaces corresponding to the unit numeral of the desired line. After the unit numeral has been transmitted the regular trunking period follows. The subscriber depressing the button P grounds No. 6 side of the line operating the relay M³ which closes the contacts m⁸ and m⁹ operating the trunking magnet V³ as before. The trunking magnet V³ this time instead of advancing series 2 but one space steps it up two spaces or to the d position. This position is the test position for determining whether the line called for is busy. If the line is busy the following conditions will prevail:

15 The contacts occupied by the wiper z³² will be grounded as I have shown it in this case for illustration. The ground being on the desired contact will complete the following circuit: ground, z³², 85 z⁴², 100, z³⁰, d, 89, d, z³⁵, 20 104, v¹⁵, v¹⁶, 105, V³, 94, to main battery B. This circuit will be maintained after the trunking period at the phone is broken, that is after the button P is released and will be maintained so long as the line is held busy.

25 While this line is held busy we have the following circuit from the busy generator G⁵: ground, G⁵, 98, v¹², v¹³, 103, z³⁷, d, 86, y, y⁵, L, 82, 55, and continued through the other switches through the calling subscriber's 30 telephone to ground. The subscriber receiving this signal knows the line called for is busy. If however, the line called for is not busy, then series 2 will return to the position c in the same manner as the A, B and C 35 switches return to the b position. We now have the trunked-through or connected position. The calling station now has connection with the line of the called station and has upon the ringing relay the proper generator current for ringing the station desired. The subscriber now depresses the ringing button P³. It will be noticed that the current supply for the transmitter T is supplied over both sides of the line to ground 40 through the M and E relays of the various switches. The battery supply from No. 5 side of the line through the transmitter circuit is as follows: 5, 151, p⁶, p⁵, 154, p⁹, p⁸, 157, 156, h¹, h², 158, through one winding of 45 50 the retardation coil N, p¹¹, p¹³, H, h, primary of the induction coil I, transmitter T to ground. The battery supply from No. 6 side of the line is as follows: 152, p³, p⁴, 153, p⁷, p¹⁵, through one winding of the retardation coil N, p¹², p¹³, H, h, primary of the induction coil I, transmitter T to ground. So long as this circuit is maintained through 55 both sides of the line to ground through the transmitter T, the E relays of the various 60 switches are energized and attract their armatures.

The subscriber in depressing the button P³ for ringing, disconnects ground from both sides of the line and the E relays of

the various switches will become deenergized. The relay E³ in connector switch D becoming deenergized, closes the contacts e¹⁰ and e¹¹ completing the circuit of the ringing relay Y by the following path: battery B, 94, Y, 99, c, z³⁰, 96, m⁷, m⁶, 97, e¹⁰, e¹¹, 70 95, to the opposite side of battery. The ringing relay Y now being energized attracts its armature, breaks the contacts y—y⁵, and y²—y⁴ and makes the contacts y—y¹, and y²—y³ placing generator current on the private normals to the called subscriber's telephone over No. 6 side of the line by the following path: G, 118, z⁴⁴, 106, y¹, y, 86, c, z³⁷, 103, v¹³, v¹⁴, 102, z⁴¹, 84, z³¹, private normal 24, and in Fig. 2, z⁵, b, 9, e¹, e⁴, 8, to 80 No. 6 side of the line to the called subscriber; and over No. 5 side of the line by the following path: G, 108, z⁴³, 107, y³, y², 87, c, z³⁸, 101, z⁴⁰, 83, z²⁰, private normal 25; and in Fig. 2, z⁴, b, 10, e³, e², 7, to No. 5 side 85 of the line to the called subscriber. It will be noticed in this case I have, for illustration, called back for a party on the same line with the calling subscriber and the button P³ being depressed disconnects his telephone, preventing him receiving the generator current for the called subscriber. In calling for a party on a different line the operation would be the same except that instead of the generator current going over 95 the private normals 24 and 25 to the calling line it would go out over another pair of private normals belonging to the particular line called for. At the end of the conversation the calling party depresses the button 100 P² placing a ground on No. 5 side of the line which energizes the M and E relays of the various switches which attracting their armatures close the circuits of their respective release magnets W which restores the 105 switches and all their parts. For tracing the circuit of the release magnet we will follow out that of W³ in the connector switch D whose circuit is closed by the following path: battery B, e¹³, e¹², 93, W³, 92, 110 m⁸, m⁹, 95, to the opposite side of battery. The circuits of the release magnets of the other switches are operated in the same manner and need not be described.

No busy signal has been provided for lines 115 that have called, as for example an operated A switch. This has not been deemed necessary because special means have been provided in the cut off springs, e⁴, e⁶ and e², e³. When switch A has operated, the normal lines 24 and 25 connected through z⁵ and z², b and b, 9 and 10, e⁵ and e³ are disconnected from e⁴ and e² which normally connect with 5 and 6 through 7 and 8, for be it remembered that E is energized during conversation. For a party calling back on his own line, this open normal circuit at e², e³ and e⁴, e⁵ does not interfere, inasmuch as the 120 125

- party called is directly on the same line 5—6, and as for ringing, where button p^3 is pressed the ground is removed from the line 5—6, the relay E is deenergized, and springs 5 e^2 , e^3 and e^4 , e^5 close, permitting the ringing current to pass over to line 5—6. The only busy test is provided in the connector switch as previously set forth. The connector does not automatically release from a busy line.
- 10 Having thus described my invention, what I claim and desire to secure by Letters Patent is:
1. In a telephone exchange system, a substation and a central station and a metallic line-circuit interconnecting them, means at the sub-station for separately grounding the two sides of the line, means to simultaneously ground both sides of the line, switching means at the central station and controlling magnets therefor having their windings directly connected to the line, one of said magnets wound and connected so that it will respond only to simultaneous grounding of both sides of the line, and another magnet wound and connected so that it will respond only to grounding of one side, whereby the switch may be controlled as desired, and substantially as described.
  2. In a telephone exchange system, a substation and a central station and a metallic line-circuit interconnecting them, means for producing current changes in either or both sides of the line, switching apparatus at the central station for interconnecting the subscribers' lines, and controlling magnets for said switching apparatus, one of said magnets responsive to current changes in one side of line, and another of said magnets irresponsible thereto, both magnets, however, being responsive to current changes in the other side of line, whereby one magnet may be actuated separately, or both magnets may be actuated together, substantially as described.
  3. In a telephone exchange system, a subscriber's station and a central station and a metallic line-circuit interconnecting them, means for producing current changes in either or both sides of the line, switching apparatus at the central station for interconnecting the subscribers' lines, and controlling magnets for said switching apparatus, one magnet responsive to current changes in either side of line, but irresponsible to simultaneous changes in both sides, the other magnet irresponsible to changes in one side of the line, but responsive to changes in the other side or in both sides, whereby with the two magnets three changes in control may be obtained, one by the energization of one magnet separately, another by the energization of the other magnet separately, and a third by the energization of both magnets, or their deener-
  - gizations in the order stated, substantially as described.
  4. In a telephone exchange system, a subscriber's station and a central station and a metallic line-circuit interconnecting them, switching apparatus at the central station for interconnecting the subscribers' lines, controlling magnets for said switching apparatus, one of said magnets bridged across the line and having its windings differential with respect to current in the same direction through both sides of the line, another of said magnets also connected in a bridge on the line and having its windings so laid on and so proportioned as to make the magnet responsive to current in the same direction in both sides of the line, but irresponsible to current in one side only, substantially as described.
  5. In a telephone exchange system, a subscriber's station and a central station and a metallic line-circuit interconnecting them, switching apparatus at the central station for interconnecting the subscribers' lines, controlling magnets for said switching apparatus, one of said magnets bridged across the line and having its windings differential with respect to current in the same direction through both sides of the line, another of said magnets also connected in a bridge on the line and having a plurality of windings so laid on, proportioned and connected to the respective line wires as to make the magnet responsive to current in the same direction in both sides of the line, irresponsible to current in one side, but responsive to current in the other side, whereby the first magnet may be separately controlled, or the second magnet may be separately controlled, or both may be controlled together, substantially as described.
  6. In a telephone exchange system, a subscriber's station and a central station and a metallic line-circuit interconnecting them, switching apparatus at the central station for interconnecting the subscribers' lines, controlling magnets for said switching apparatus, one of said magnets bridged across the line and having its windings differential with respect to current in the same direction through both sides of the line, another of said magnets also connected in a bridge on the line and having its windings divided into three parts, two parts connected together, differentially laid on with regard to each other, and the third part sufficient to overbalance and operatively energize the magnet; one of the first two parts being connected to each side of the line, and the third part from their point of union to battery or ground, substantially as described.
  7. In a telephone exchange system, a substation and a central station and a metallic line-circuit interconnecting them, means for

producing current changes in either or both sides of the line, switching apparatus at the central station for interconnecting the subscribers' lines, and controlling magnets for said switching apparatus, one of said magnets responsive to current changes in one side of line, and another of said magnets irresponsive thereto, both magnets, however, being responsive to current changes in the other side of line, whereby one magnet may be actuated separately, or both magnets may be actuated simultaneously, together with operative connections for the switching mechanism controlled by the magnets separately, and restoring or release mechanism controlled by them jointly, substantially as described.

8. In a telephone exchange system, a subscriber's station and a central station and a metallic line-circuit interconnecting them, means for producing current changes in either or both sides of the line, switching apparatus at the central station for interconnecting the subscribers' lines, and controlling magnets for said switching apparatus, one magnet responsive to current changes in either side of line, but irresponsive to simultaneous changes in both sides, the other magnet irresponsive to changes in one side of the line, but responsive to changes in the other side or in both sides, whereby with the two magnets three changes in control may be obtained, one by the energization of one magnet separately, another by the energization of the other magnet separately, and a third by the energization of both magnets, or their deenergizations in the order stated, together with means for operating the switching apparatus controlled separately and in sequence by said magnets, and means for releasing or restoring the switching apparatus to normal inoperative condition, controlled by the said magnets jointly, substantially as described.
9. In a telephone exchange system, a subscriber's station and a central station and a metallic line-circuit interconnecting them, switching apparatus at the central station for interconnecting the subscribers' lines, controlling magnets for said switching apparatus, one of said magnets bridged across the line and having its windings differential with respect to current in the same direction through both sides of the line, another of said magnets also connected in a bridge on the line and having its windings so laid on and so proportioned as to make the magnet responsive to current in the same direction in both sides of the line, but irresponsive to current in one side only, together with means for operating the switching apparatus controlled separately in sequence by said magnets, and means for releasing or restoring the switching apparatus to normal

inoperative condition, controlled by the said magnets jointly, substantially as described.

10. In a telephone exchange system, a subscriber's station and a central station and a metallic line-circuit interconnecting them, switching apparatus at the central station for interconnecting the subscribers' lines, controlling magnets for said switching apparatus, one of said magnets bridged across the line and having its windings differential with respect to current in the same direction through both sides of the line, another of said magnets also connected in a bridge on the line and having its windings so laid on and so proportioned as to make the magnet responsive to current in the same direction in both sides of the line, irresponsive to current in one side, but responsive to current in the other side, whereby the first magnet may be separately controlled, or the second magnet may be separately controlled, or both may be controlled simultaneously, together with means for operating the switching apparatus controlled separately in sequence by said magnets, and means for releasing or restoring the switching apparatus to normal inoperative condition, controlled by the said magnets jointly, substantially as described.

11. In a telephone exchange system, a subscriber's station and a central station and a metallic line circuit interconnecting them, switching apparatus at the central station for interconnecting the subscribers' lines, controlling magnets for said switching apparatus, one of said magnets bridged across the line and having its windings differential with respect to current in the same direction through both sides of the line, another of said magnets also connected in a bridge on the line and having its windings divided into three parts, two parts connected together, differentially laid on with regard to each other, and connected to opposite sides of line; the third part sufficient to overbalance and inoperatively energize the magnet and connected from the point of union of the other two parts to battery or ground; together with means for operating the switching apparatus controlled separately in sequence by said magnets, and means for releasing or restoring the switching apparatus to normal inoperative condition, controlled by the said magnets jointly, substantially as described.

12. In a telephone exchange system, a subscriber's station and a central station, with a metallic line circuit interconnecting them, means at the subscriber's station for producing current changes in either side of the line, switching apparatus at the central station for interconnecting the lines, and a pair of relays connected to each line, one of said relays adapted to respond to current

changes in one side of line, the other to changes in both sides of the line, controlling magnets for the switching apparatus and circuits therefor adapted to be separately closed and opened by the said relays respectively, whereby the subscriber may produce operative actuation of the switching apparatus by sending current impulses in one side or both sides of line, substantially as described.

13. In a telephone exchange system, a subscriber's station and a central station, with a metallic line-circuit interconnecting them, means at the subscriber's station for producing current changes in either side of line, switching apparatus at the central station for interconnecting the lines, and a pair of relays connected to each line, one of said relays adapted to respond to current changes in one side of line, the other to changes in both sides of the line, controlling magnets for the switching apparatus and circuits therefor adapted to be separately closed and opened by the said relays respectively, together with a release or restoring magnet and a circuit therefor controlled jointly by the relays, substantially as described.

14. In a telephone exchange system, a subscriber's station and a central station with a metallic line circuit interconnecting them, a source of current supply at the central station common to two or more lines, switching apparatus at the central station for interconnecting the lines, a controlling magnet for said switching apparatus bridged across the line and having an intermediate point on its windings connected through said source to ground, a telephone transmitter at the subscriber's station connected on one side through impedance to both sides of the line, and on its other side to ground, including in its circuit the primary of an induction coil, the secondary thereof being bridged across the line outside the impedance, and means controlled by the subscriber for determining the current flow in one or both sides of the line, substantially as described.

15. In a telephone exchange system, a subscriber's station and a central station and a metallic line-circuit interconnecting them, automatic switching apparatus at the central station for interconnecting the lines, a controlling magnet therefor, a common source of current supply for two or more lines, said source connected from ground to both sides of each subscriber's line, the windings of the controlling magnet of the switching apparatus being included in the bridge thus formed, a telephone transmitter at the subscriber's station directly connected from both sides of line to ground to derive its current supply, and inductively connected across the two sides of line for transmitting speech, together with means

controlled by the subscriber for determining the current flow in one or both sides of the line, substantially as described.

16. In a telephone exchange system, a subscriber's station and a central station and a metallic line circuit interconnecting them, means at the subscriber's station for producing current changes in either or both sides of the line according to a predetermined code, and switching apparatus at the central station comprising two elements, the first determining the functions of the second and the second testing to determine and select idle apparatus for further connection, together with separate controlling magnets for said two elements, and means to actuate the same in accordance with the current changes in the line, substantially as described.

17. In a telephone exchange system, a subscriber's station and a central station and a metallic line-circuit interconnecting them, means at the subscriber's station for producing current changes in either or both sides of the line according to a predetermined code, and switching apparatus at the central station comprising two elements, the first determining the functions of the second and the second testing to determine and select idle apparatus for further connection, together with separate controlling magnets for said two elements, and means to actuate the same in accordance with the current changes separately produced in the two sides of line, and a release or restoring magnet for both elements actuated in accordance with simultaneous changes produced in both sides of the line, substantially as described.

18. In an automatic telephone exchange system, a switching apparatus comprising as elements, a selector switch, a controlling switch and a test switch, the selector switch determining the specific group of trunk or other circuits to be selected, the controlling switch placing the test switch in operative condition, and the latter adapted thereupon to automatically determine and connect with an idle unit in the selected group, together with a controlling magnet for each of said elements, means at the subscriber's station for actuating said controlling magnets, and means actuated by the magnet of the controlling switch to lock itself after initial actuation, substantially as described.

19. In an automatic telephone exchange system, a switching apparatus comprising as elements, a selector switch, a controlling switch and a test switch, the selector switch determining the specific group of trunk or other circuits to be selected, the controlling switch placing the test switch in operative condition, and the latter adapted thereupon to automatically determine and connect with an idle unit in the selector group, together with a controlling magnet for each of said

elements, means at the subscriber's station for actuating said controlling magnets, and means actuated by the magnet of the controlling switch to lock itself after initial actuation, and a release magnet for unlocking the same and returning of the elements to their initial or normal condition, substantially as described.

In testimony whereof I affix my signature in presence of two witnesses.

WILLIAM RAGAN BINKLEY.
